INTERNAL COMBUSTION ENGINE

Lars J. Istad, Roselle Park, N. J.

Application March 15, 1938, Serial No. 195,951

20 Claims. (Cl. 123—58)

This invention relates to improvements in engines generally, and more particularly to engines of the internal combustion type operating on the two stroke cycle.

5 One object of this invention is an improved construction of the type of engine in which a plurality of cylinders are arranged around a crank shaft parallel to each other and to the crank shaft, providing a compact construction of short 10 transverse and longitudinal dimensions.

Another object of the invention is an improved fuel mixture and scavenging air controlling valve for engines generally but is especially applicable to engines in which the cylinders are arranged 15 about the crank shaft.

Still another object of the invention is a simplified and improved construction for super-charging and scavenging the cylinders.

Among other objects of the invention are improved means for holding wobble plates against rotation, improved means for facilitating the removal of the wobble plates and their bushings from the crank shaft, and improved thrust bearings for receiving the thrust of the wobble plates 25 as they are rocked by the operation of the pistons.

Other objects of the invention will appear from the following description taken in connection with the drawings, in which:

Fig. 1 is a longitudinal vertical section through 30 the engine block, taken substantially on the line 1—1 Figs. 2 and 4;

Fig. 2 is a composite view of transverse vertical sections taken on the lines 2, 2A and 2B of Fig. 1;

Fig. 3 is a section on the line 3—3 of Fig. 2;

Fig. 4 is a composite sectional view taken on the lines 4, 4A, 4B, 4C, of Fig. 1;

Fig. 5 is a side elevation of the valve;

Fig. 6 is a transverse vertical section on the line 6—6 of Fig. 5;

Fig. 7 is a transverse vertical section on the line 7—7 of Fig. 5;

Fig. 8 is a transverse vertical section on the line 8—8 of Fig. 5;

Fig. 9 is a transverse vertical section on the line 9—9 of Fig. 5;

Fig. 10 shows the valve grooves and ports and the cooperating cylinder ports developed in a plane;

Fig. 11 is a side view of a crank shaft in which the cranks are out of phase;

Fig. 12 is a section on the line 12—12 of Fig. 11;

Fig. 13 is a section on the line 13—13 of Fig. 11;

Fig. 14 is a detail longitudinal section of a portion of the valve and adjacent cylinders; and

Fig. 15 is a view corresponding to a portion of

Fig. 1 showing a valve adapted for use in a Diesel engine.

For the purpose of disclosure I have illustrated a preferred form of my invention. The engine block may comprise a main casting 15 provided with six cylinders 16, Fig. 4, extending from end to end of the casting and arranged around a central cylindrical opening 17, Fig. 1, in which is mounted a cylindrical extension 18 of a supplemental casting 19 provided with six cylinders 20 of larger diameter than that of cylinders 16, extending from end to end of this casting and in axial alignment with the cylinders 16 of the main casting 15. The bores of the casting 19 and extension 18 are preferably aligned and have continuous walls. If desired the extension 18 may be made separate and extend into a bore in the casting 19. The castings 15 and 19 may be held together by rods 24 and nuts 25. Reduced extensions 26 on the rods 24 pass through end castings 27 and 28, and nuts 29 on the rods 24 secure the end castings 27 and 28 to the castings 15 and 19. A single casting may be used instead of the castings 15 and 19.

Mounted inside of the cylindrical extension 18 of the casting 19 and midway of the ends of the engine block is a short cylindrical member 30 provided with a bushing 31, constituting the center bearing for a crank shaft 32. The center bearing member 30 may be held against rotational and longitudinal movement with respect to the extension 18 by means of one or more bolts 33 as indicated.

The crank shaft 32 is provided with angular cranks 35 and 36 having their high portions adjacent the center bearing 30, and with end bearing portions 37 and 38 which rotate in bushings 39 and 40 supported in thrust members 41 and 42 which are preferably pressed into tubular extensions 43 and 44 on the end castings 27 and 28. One end of the crank shaft may be provided with a fly wheel 45, and various mechanisms, such as the distributor and oil pump and so forth may be operated from this end of the shaft.

Mounted within each of the cylinders 16 are pistons 50 and 51. These pistons are connected by ball and socket connections with the piston rods 52 and 53 which in turn are connected by ball and socket connections 54 and 55 with 50 arms 56 and 57 of wobble plates 58 and 59. The wobble plates are provided with cylindrical bearing portions 60 and 61 surrounding the angular cranks 35 and 36. Two sets of spaced opposed semi-cylindrical exteriorly convexed bush-

ings 62 and 63 bear on the cranks and are held spaced by a continuous cylindrical member 64, provided interiorly with concave cooperating surfaces. The parts are retained in place by a thrust ring 65 which is retained in place by a threaded retaining ring 66. The engaging cooperating faces of the thrust rings 65 and the thrust members 41 and 42 are frusto-conical with radial lines intersecting the angle between the axis of the adjacent crank and the axis of the end bearing of the crank shaft so that the wobble plate will roll on the thrust plates without any sliding movement between the engaging faces.

15 The pistons 51 in the right-hand ends of the cylinders 16 as shown in Fig. 1, control exhaust ports 70 through which the burnt gases are forced by scavenging air as will be described later. In the drawings I have applied to the 20 ports, grooves, etc., the small letters *a*, *sa*, *e*, *f* and *cf*, to designate respectively, air, scavenging air, exhaust gases, fuel and compressed fuel.

The pistons 50 in the left-hand ends of the cylinders 16 Fig. 1, control the scavenging ports 25 71. Each piston has an enlarged portion or flange 72 which operates in the cylinder 20 in the casting 19. The flange 72 and piston 50, the wall of the cylinder 20, and the end of the casting 15 define a super-charging chamber 73. 30 The flange 72, the wall of the cylinder 20 and the closed end 74 of the cylinder 20 define a scavenging chamber 75 into which scavenging air is drawn and compressed and then forced through a port 76 in the wall of the cylinder 20 35 and the port 71 into the cylinder 16 for the purpose of scavenging the cylinder of burnt gases. The closed end 74 of the cylinder 20 comprises a cup-shaped member 77 provided with an annular slot 78 formed by a flange on said 40 member and a disk 79 secured thereto, to receive an annulus 80 on a cup member 81 which together with a similar removable cup member 82 constitutes a socket for a two part ball member 83 through which the piston rod 52 operates, a 45 sealing ring 84 being provided to effect an air tight seal between the ball 83 and the rod 52. This construction closes the end 74 of the cylinder 20, forms an effective seal with the piston rod 52, and permits reciprocating and angular 50 movement of said rod.

The wobble plate 58 is held against rotation by sliding plates 85 Fig. 3 provided with sockets cooperating with the spherical end of the arm 56 and which slide on tracks 86 supported upon 55 extensions 87 projecting from the end wall of the casting 27. These tracks 86 are connected by a head 88 which constitutes the closure for the end wall of the casting. The casting 28 is also provided with a similar construction for preventing rotation of the wobble plate 57. Neither 60 has been disclosed in Fig. 1 as the former lies directly behind the parts 31, 41 and 43, and the latter directly behind the parts 38, 42 and 44. These constructions are preferably angularly 65 aligned. Suitable ignition mechanism may be employed and when the engine is used as a gas engine the spark plug may be located as shown in Fig. 1. If the engine is used as a fuel oil engine the spark plug may be removed and replaced by a 70 fuel oil spray injecting mechanism as is well understood.

The walls of the cylinder 20 are also provided with scavenging air intake ports 90, ports 91 through which fuel mixture is sucked into the 75 chamber 73 and through which it is ejected into

the space between the pistons 50 and 51 through ports 92 in the cylinder 16.

The casting 19 is provided with a scavenging air inlet 93 and a fuel mixture inlet 94. For the purpose of controlling the admission of the air and the fuel mixture into the various cylinders at the proper time, I have provided a single cylindrical valve 95 mounted in and having a clearance fit with the wall of the cylindrical opening in the casting 19. The wall of the valve is thickened 10 at 96 to provide a counter-weight for the crank 35 and is secured by three bolts 97 to a disc 98 secured to or integral with the crank shaft, the disc 98 fitting within the cylindrical opening in one end of the valve 95. The crank shaft is preferably provided with a semi-cylindrical member 99 to counter-balance the crank 36, and which is secured to an enlarged portion 100 on the crank shaft by three bolts 101.

As disclosed in Fig. 5 the valve 95 is provided with a continuous groove 105 which is always in communication with the scavenging air intake 93. This groove which is shown in Figs. 7 and 14 communicates by means of a lateral port 106 with an interrupted groove 107, Fig. 6, through 20 which scavenging air is sucked into the chamber 75 when it registers with the scavenging air intake port of this cylinder. The length of the groove 107 is such as to overlap several of the ports 90 leading to the chambers 75. The interrupted portion of the groove seals the chamber 75 as the piston 50 moves towards the left so that the air sucked into the chamber 75 is compressed therein and is forced out through the port 76 and through the port 71 when the latter 35 has been uncovered by the piston 50, into the space between the pistons 50 and 51 and out through the exhaust ports 70 thereby scavenging the cylinder 16 of burnt gases.

The valve 95, Fig. 5, is also provided with a 40 continuous groove 110 which is always in communication with the fuel supply intake 94 and which communicates with an interrupted groove 111 (see also Fig. 8) which at the proper time registers with the port 91 communicating with 45 the chamber 73 on the forward side of the flange 72 of the piston so that fuel is drawn into the chamber 73 as the flange 72 of the piston 50 moves towards the left (Fig. 1). The communicating duct between the grooves 110 and 111 is 50 shown by a broken line in Fig. 14.

The valve 95 is also provided with an interrupted groove 112 Figs. 5 and 8, see also Fig. 14, which registers with the port 91 at the proper time during movement of the piston to the right, 55 Fig. 1. This groove communicates with a short groove 113 which registers with the port 92 in the cylindrical casting 18 and cylinder 16 at the proper time to provide a passage for the transfer of compressed fuel from the chamber 73 into 60 the space between the pistons 50 and 51 of the cylinder 16. The grooves 110 and 111 establish communication between the fuel intake 94 and the chamber 73 and the grooves 112 and 113 establish communication between the chamber 73 65 and the space between the pistons 50 and 51. The groove 112 overlaps the ports 91 of several cylinders with the result that the fuel compressed in the chamber 73 near the end of the stroke of the piston 50 is transferred to the cylinder 16 with which the groove 113 registers at 70 that time.

By means of the construction shown the valve controls the admission of scavenging air into the chambers 75, the admission of fuel into the 75

chambers 73 and the transfer of the compressed fuel from the chambers 73 into the cylinders 16. The same valve exercises the same control over the various cylinders in succession with the result that fuel will be drawn into the chambers 73 in succession and compressed therein in the same order and delivered into the cylinders 16 in the same order, and scavenging air will be drawn into the chambers 75 in succession and compressed therein in the same order. The pistons 51 control the exhaust ports 70 and the pistons 50 control the admission of fuel and scavenging air into the cylinders 16. Both the fuel and scavenging air are compressed when transferred into the cylinders 16.

In Fig. 10 I have shown the valve developed in a plane and also the ports in the cylinders 16 and 20 and on this and other figures have indicated the course taken by the scavenging air 0 by the small letters *a* and *sa*, and *e* and the course taken by the fuel mixture by the small letters *f* and *cf*.

In the main disclosure I have shown the right-hand crank 36 in phase with the left-hand crank 35 (Fig. 1) but in actual operation the crank 36 will be located 20 degrees ahead of the crank 35 as indicated in Figs. 11, 12 and 13.

I have described the engine as being a gas engine but it is obvious that the same could be 0 used as a fuel oil engine by replacing the spark plugs by oil spraying and injecting devices 114. In case the engine is used as a fuel oil engine, 1 may use a valve 95a provided with single groove 115 instead of the grooves 105 and 110 and an air supply inlet 116 instead of the air and gas inlets 93 and 94 but otherwise the valve construction will be practically the same. The chamber 75 will be used for scavenging purposes as before and the chamber 73 will be used for forcing 0 air under pressure into the space between the pistons 50 and 51 for scavenging and/or super-charging.

The semi-cylindrical bushings 62 and 63 which are convexed exteriorly together with the cylindrical member 64, the end of the sleeves 63 and the thrust members 65 which are complementarily concaved interiorly, constitute self aligning bearings for the wobble plates whereby the thrust from the wobble plates on the angular cranks 0 will be uniformly distributed over a large area of the surface of the cranks.

By locating the angular or conical cranks as close to the center bearing as possible the overall length of the engine will be held to a minimum. 5 This permits the wobble plates to be mounted close to the ends of the main engine castings permitting the use of a relatively short crank shaft and relatively short piston rods and shallow end castings. Only a small additional space is 10 required for mounting the valve in the position disclosed in the drawings, and the valve may be directly connected to the crank shaft thereby avoiding a train of valve actuating connections. This mounting of the valve also simplifies the 15 construction of the inlet air and fuel mixture ports and the construction of the grooves of the valve which establish communication between said ports and the ports in the engine cylinder, and in the fuel mixture compression and scavenging air compression chambers. The cylindrical valve has an extended clearance fit in the casting 19 and is wholly located within this casting providing for a compact construction and making it feasible to construct the valve as a 20 single unit, and to arrange the grooves and in-

terrupted portions thereof so that the air may be drawn into the scavenging chambers concurrently and be compressed and delivered therefrom concurrently, and so that the fuel mixture may be drawn into the fuel mixture compression chambers and be compressed therein concurrently, and delivered therefrom concurrently into the associated engine cylinders and adjacent engine cylinders.

By constructing the groove 112 to register with the ports 91 of several fuel mixture compression chambers, the fuel mixture that is compressed in one fuel mixture compression chamber is delivered not only to the associated engine cylinder but also to the next adjacent engine cylinder. The interrupted portion of the groove 113 prevents any of the exhaust or scavenging air from being forced back into the fuel mixture compression chambers or into the fuel line or into the adjacent engine cylinders. The groove 20 113 begins to register with the port 92 of a cylinder after the scavenging of that cylinder has been completed and is brought into full registry preferably approximately as the scavenging air inlet port 71 is being closed by the piston 50 25 and after the exhaust port 70 has been closed by the piston 51 thereby preventing any waste of fuel mixture. As disclosed the exhaust port 70 is opened before the scavenging intake port 71 is 30 opened so that the cylinder may be scavenged freely immediately upon opening of the port 71.

The phase relation of the cranks may be varied from that shown as may also the size and location of the various grooves and ports of the valve and cylinders. The crank shaft may be provided with lubricant distributing ducts through which a lubricant may be forced to the various bearings. Any suitable means may be provided for lubricating the valve and other movable parts. The center bearing 30 may, as shown, be provided with a groove and duct to prevent excess or used lubricant from reaching the valve. Instead of the wobble plates disclosed I may employ 40 "swash" plates or other equivalents.

While I have described my invention with reference to a specific disclosure on the drawings, it is to be understood this is a preferred embodiment and that various changes may be made without departing from the spirit of my invention and that certain features disclosed may be applicable to other types of gas and fuel oil engines. It is also to be understood that the cylinder block may be made rotatable and mechanism may be driven from the rotating cylinder block in which case of course the crank shaft would be held against rotation. Minor changes would be necessary to establish a connection between the fuel intake port 94 and the carburetor. Certain features are applicable to engines operated by fluids under pressure and in broader aspects of my invention the valve may be indirectly operated by the crank shaft or otherwise and may control more or fewer cylinders bearing a different relation to the crank shaft and in which the valve may be arranged variously with respect to 55 the crank shaft and cylinders.

I claim:

1. The combination of an engine shaft, a cylinder block provided with a plurality of engine cylinders arranged around and parallel to said shaft and provided with a cylindrical opening surrounding said shaft, angular cranks on said shaft, opposed pistons within said cylinders, means for transferring movement from said pistons to said cranks, a cylindrical valve mounted 70 75

- in said cylindrical opening within said block and surrounding one of said cranks, means connecting said valve to said shaft, said cylinders having ports for the admission of fuel, said block being provided with a fuel supply port, and said valve being provided with means cooperating with said ports for controlling the admission of fuel into said cylinders and means for exhaust.
2. The combination of an engine shaft, a cylinder block provided with a plurality of engine cylinders arranged around and parallel to said shaft and provided with a cylindrical opening surrounding said shaft, an angular crank on said shaft, pistons in said cylinders, means for transferring movement from said pistons to said crank, a cylindrical valve mounted in said cylindrical opening within said block and surrounding said crank, and means connecting said valve to said shaft, said cylinders having ports for the admission of fuel, said block being provided with a fuel supply port, and said valve being provided with means cooperating with said ports for controlling the admission of fuel into said cylinders.
3. In combination with a two cycle engine comprising an engine shaft and a plurality of parallel cylinders spaced from and arranged concentrically about the engine shaft, a cylindrical valve seat within the space defined by said cylinders and provided with a plurality of ports communicating with said cylinders, and a cylindrical valve surrounding and connected to said shaft and cooperating with said cylindrical seat, said valve being provided with a single port in constant communication with a source of fluid supply and adapted to be brought into registry serially with said ports.
4. In combination with an engine comprising an engine shaft and a plurality of parallel cylinders spaced from and arranged concentrically about the engine shaft, a cylindrical valve seat within the space defined by said cylinders and provided with a plurality of ports communicating with said cylinders, and a cylindrical valve surrounding and connected to said shaft and cooperating with said cylindrical seat, said valve being provided with a port in constant communication with a source of fluid supply adapted to be brought into registry serially with said ports, said port in said valve being of sufficient length to register simultaneously with a plurality of said ports.
5. In combination with a two cycle engine comprising an engine shaft and a plurality of parallel cylinders spaced from and arranged concentrically about the engine shaft, a cylindrical valve seat within the space defined by said cylinders and provided with a fluid supply port and a plurality of ports communicating with said cylinders, and a cylindrical valve surrounding and connected to said shaft and cooperating with said cylindrical seat, said valve being provided with a single port in constant communication with said fluid supply port and adapted to be brought into registry serially with said ports communicating with said cylinders.
6. In combination with an engine comprising an engine shaft and a plurality of parallel cylinders spaced from and arranged concentrically about the engine shaft, a cylindrical valve seat within the space defined by said cylinders provided with a fluid supply port and with a plurality of ports communicating with said cylinders, and a cylindrical valve surrounding and connected to said shaft and cooperating with said cylindrical seat, said valve being provided with a continuous

groove in constant communication with said fluid supply port, and with an interrupted groove in communication with said continuous groove and adapted to be brought into registry serially with said ports, said interrupted groove in said valve being of sufficient length to register simultaneously with a plurality of said ports.

7. In an engine comprising an engine shaft and a series of engine cylinders arranged concentrically about the engine shaft and a series of fuel compression cylinders also arranged concentrically about said engine shaft, pistons in said engine and fuel compression cylinders operatively connected together and to said engine shaft, a cylindrical valve seat within the space defined by said cylinders, ported for communication with a source of fuel supply and with said fuel compression cylinders and also ported for the admission of compressed fuel from said fuel compression cylinders, into said engine cylinders, a cylindrical valve surrounding and operatively connected to said engine shaft cooperating with said valve seat, said valve being provided with an interrupted groove in constant communication with the fuel supply port and adapted to be brought into registry with the ports communicating with said fuel compression cylinders, said valve also being provided with an interrupted groove adapted to be brought into communication with the ports communicating with said fuel compression cylinders and said engine cylinders.

8. In an engine comprising an engine shaft and a series of engine cylinders disposed concentrically about the engine shaft and a series of fuel compression chambers also arranged concentrically about said engine shaft, pistons in said engine and fuel compression cylinders operatively connected together and to said engine shaft, a cylindrical valve seat within the space defined by said cylinders, ported for communication with a source of fuel supply and with said fuel compression cylinders and also ported for the admission of fuel into said engine cylinders, a cylindrical valve surrounding and operatively connected to said engine shaft cooperating with said valve seat, said valve being provided with an interrupted groove in constant communication with the fuel supply port and adapted to be brought into registry with the ports communicating with said compression cylinders, said valve also being provided with interrupted intercommunicating grooves adapted to be brought into registry with the ports communicating with said fuel compression cylinders and said engine cylinders, said first mentioned and said last mentioned interrupted grooves being disposed at opposite sides of said valve and said first mentioned groove adapted to be brought into registry with the ports in said compression cylinders being of a length to communicate with a plurality of said ports leading into said compression cylinders simultaneously.

9. In an engine comprising an engine shaft and a series of groups of cylinders disposed concentrically with respect to said engine shaft, each group of cylinders comprising an engine cylinder, a fuel compression cylinder and a scavenging air compression cylinder, piston means operating in said cylinders and operatively connected together and to said engine shaft, a cylindrical valve seat disposed within said groups of cylinders ported for communication with said cylinders, a cylindrical valve surrounding and operatively connected to said engine shaft and cooperating with said cylindrical seat, said seat being also ported

to establish communication with a source of fuel supply and the atmosphere, said valve being provided with an interrupted groove in constant communication with the port leading to the atmosphere and adapted to register with the ports communicating with the scavenging air compression cylinders, said valve also being provided with an interrupted groove in constant communication with a fuel supply port and adapted 5 to be brought into registration with the ports communicating with the fuel compression cylinders, said valve also being provided with interrupted grooves adapted to be brought into registration with the ports leading to said engine 10 cylinders and the ports communicating with said fuel compression cylinders.

10. In an engine comprising an engine shaft and a series of groups of cylinders disposed concentrically with respect to the engine shaft, each 20 group of cylinders comprising an engine cylinder, a fuel compression cylinder and a scavenging air compression cylinder, piston means operating in said cylinders and operatively connected together and to said engine shaft, a cylindrical valve seat disposed within said groups of cylinders ported for communication with said cylinders, a cylindrical valve surrounding and operatively connected to said engine shaft and cooperating with said cylindrical seat, said seat 25 being also ported to establish communication with a source of fuel supply and the atmosphere, said valve being provided with an interrupted groove in constant communication with the port leading to the atmosphere and adapted to register 30 with the ports communicating with the scavenging air compression cylinders, said valve also being provided with an interrupted groove in constant communication with said fuel supply port and adapted to be brought into registration with the ports communicating with the fuel compression cylinders, said valve also being provided 35 with interrupted intercommunicating grooves adapted to be brought into registration with the ports leading to said engine cylinders and with the ports communicating with said fuel compression chamber, said interrupted grooves cooperating with the ports in said scavenging air and fuel compression chambers being of a length to register simultaneously with a plurality of said 40 ports.

11. A cylindrical valve having an exterior cylindrical valve face provided with circumferentially continuous and interrupted intercommunicating grooves and intercommunicating interrupted grooves located diametrically opposite said first mentioned interrupted groove with one of said latter interrupted grooves in the same plane as said first mentioned interrupted groove.

12. A cylindrical valve having an exterior cylindrical valve face provided with circumferentially continuous and interrupted intercommunicating grooves and intercommunicating interrupted grooves located diametrically opposite said first mentioned interrupted groove with one 65 of said latter interrupted grooves in the same plane as said first mentioned interrupted grooves, the other of said second mentioned interrupted grooves being of a length to communicate serially individually with ports and said interrupted 70 grooves located in the same plane being of a length to communicate serially with a plurality of ports simultaneously.

13. The combination in an engine of an engine shaft, a plurality of scavenging air compression cylinders and a plurality of engine cylinders,

pistons in corresponding scavenging and engine cylinders operatively interconnected and operatively connected to said engine shaft, said cylinders being provided with inlet ports, and a single valve element operatively connected to said shaft 5 for controlling the admission of fluid into said cylinders in proper timed relation, said corresponding scavenging air compression and engine cylinders being provided with intercommunicating ports for transferring compressed scavenging 10 air directly from the former to the latter, said latter ports in said engine cylinders being controlled by the pistons in said engine cylinders.

14. The combination in an engine of an engine shaft, a plurality of fuel compression and 15 engine cylinders, pistons operating in said cylinders operatively interconnected and operatively connected to said engine shaft, each fuel compression cylinder being provided with a port for the admission and expulsion of fuel and each engine cylinder being provided with a port for the admission of fuel, and a single valve operatively connected to said engine shaft operating to control the admission of fuel into said fuel compression cylinders and transfer of compressed 20 fuel from said fuel compression cylinders into said engine cylinders.

15. The combination of an engine shaft, a plurality of engine cylinders arranged about said shaft in spaced concentric relation thereto, a 30 crank on said shaft located within the confines of said cylinders, said cylinders being provided with ports, and a valve for controlling said ports operatively connected to said shaft and surrounding said crank and weighted to counterbalance 35 said crank, said valve provided with a thickened portion having an eccentrically located hole therein, a projection on said shaft also provided with an eccentrically located hole to cooperate with said hole in said thickened portion of the 40 valve, and means through said cooperating holes securing said thickened portion of said valve to said projection on the shaft.

16. The combination in an engine, of an engine shaft, a plurality of engine cylinders, pistons in said cylinders operatively connected to said shaft, said cylinders being provided with fuel inlet ports, positioned to be unmasked by the respective pistons during the out-stroke of the pistons, and a single valve element for preventing 50 flow of gases of explosion through said ports as they are unmasked by the pistons during their out-stroke and for admitting fuel to said ports during the in-stroke of the pistons while the ports remain unmasked by said pistons.

17. The combination in an engine, of an engine shaft, a plurality of engine cylinders, pistons in said cylinders operatively connected to said shaft, said cylinders being provided with fuel inlet ports and scavenging air inlet ports adapted 60 to be unmasked by said pistons in the order stated during the out-stroke of the pistons, and a single valve operating to connect said fuel inlet ports with a source of fuel supply during the in-strokes of the pistons after the pistons have 65 masked the scavenging air inlets and to disconnect said source of fuel supply from said fuel inlet ports to prevent exploded gases and scavenging air from entering said source of fuel supply during the outstroke and unmasking of the fuel 70 inlet ports by said pistons.

18. An engine comprising a series of cylinders including a combustion cylinder, an over-compression cylinder and a scavenging cylinder, interconnected pistons in said cylinders, said scav-

enging and combustion cylinders being provided with interconnected ports and said over-compression cylinder and combustion cylinder being provided with interconnected ports, said ports in 5 said combustion cylinder being located near the outer end of the cylinder and so relatively arranged that the port admitting fluid from the over-compression cylinder is opened by the piston in the combustion cylinder before the port 10 admitting fluid from the scavenging cylinder is opened during the outward stroke of the piston, and a valve controlling the admission of fluid into the scavenging and over-compression cylinders and from the over-compression cylinder into the 15 combustion cylinder, said valve operating to interrupt communication between the interconnected ports connecting the over-compression cylinder to the combustion cylinder during the outward stroke of the piston and to connect said 20 ports during the inward stroke of the piston after the port admitting scavenging air into the combustion cylinder has been closed by the piston during its inward stroke.

19. An engine comprising a series of cylinders 25 including a combustion cylinder, an over-compression cylinder and a scavenging cylinder, interconnected pistons in said cylinders, said scavenging and combustion cylinders being provided with interconnected ports and said over-compression cylinder and combustion cylinder being provided with interconnected ports, said ports in 30 said combustion cylinder being located near the outer end of the cylinder and so relatively arranged that the port admitting fluid from the over-compression cylinder is opened by the piston 35 in the combustion cylinder before the port admitting fluid from the scavenging cylinder is opened during the outward stroke of the piston, a valve controlling the admission of fluid into the scavenging and over-compression cylinders and from the over-compression cylinder into the 40 combustion cylinder, said valve operating to interrupt communication between the interconnected ports connecting the over-compression cylinder to the combustion cylinder during the 45 outward stroke of the piston and to connect said ports during the inward stroke of the piston

after the port admitting scavenging air into the combustion cylinder has been closed by the piston during its inward stroke, an opposed piston mounted in said combustion cylinder, an engine shaft, and connections between said pistons and 5 said engine shaft, said pistons moving in opposite directions and said combustion cylinder being provided with exhaust ports adapted to be uncovered by said last mentioned piston during its outward stroke and to be covered by said 10 piston substantially at the time that masking of the scavenging port has been effected by the other piston in the combustion cylinder and admission of over-compressed fluid into the combustion cylinder from said over-compression 15 cylinder is started under control of the valve.

20. In a barrel type engine comprising a cylinder block, said block having a plurality of cylinders arranged in a circle along the outer periphery of the block and being all parallel to the 20 axis of the block, said block also having a central cylindrical space coaxial with the block and forming a cylindrical valve seat; a crank shaft journaled at the axis of said cylinder block; a pair of opposed pistons in each of said cylinders, 25 the cylinders and pistons at one end of the block being of the stepped type and providing supercharging chambers between the larger diameter parts of the pistons and the cylinder block; closures fitted in the ends of the stepped cylinders 30 having the stepped pistons thereby forming scavenging chambers between said closure and the larger diameter part of the stepped piston; means for transferring the linear motion of the 35 said pistons to a rotational motion of said crank shaft; a cylindrical valve located in said valve seat and rotatable by said crank shaft, said valve being circumferentially grooved, intake means communicating with the grooves of said valve, and said block being provided with inlet 40 ports communicating with said supercharging and scavenging chambers and controlled by said valve and inlet ports communicating with the explosion chambers of the cylinders and governed by the coordinated operation of said pistons and cylindrical valve.
